UNITED STATES PATENT OFFICE

2,125,842

REFRIGERATING APPARATUS

Lewis W. Eggleston, Detroit, Mich., assignor to
 Detroit Lubricator Company, Detroit, Mich., a
 corporation of Michigan

Application April 3, 1936, Serial No. 72,608

3 Claims. (Cl. 62—115)

My invention relates generally to refrigerating apparatus and more particularly to systems wherein the condenser of a refrigerating apparatus is cooled by the water of a domestic water supply system.

One of the objects of my invention is to provide a liquid circulatory system for absorbing and conveying heat from a refrigerant condenser for transfer to the water of a domestic water supply system.

Another object of my invention is to provide for the cooling of a refrigerant condenser by the water of a domestic water supply system without danger of contaminating the water by the refrigerant medium in the event of a leak in the refrigerant condenser.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated my invention, in which drawings—

Figure 1 is a diagrammatic view of a cooling system embodying my invention;

Fig. 2 is a view shown in cross section taken along the line 2—2 of Fig. 1;

Fig. 3 is a diagrammatic view of a modification of the system of Fig. 1, and

Fig. 4 is a diagrammatic view of another modification embodying my invention.

Referring to the drawings by characters of reference and first to Fig. 1, the numeral 1 designates a storage tank or container of a domestic cold water supply system, the tank 1 having an inlet 2 preferably adjacent its lower end and having an outlet 3 preferably in its top wall.

Normally the tank 1 is completely filled with cold water for supply to spigots and other outlets (not shown) of a domestic water supply system of a building. Associated with the tank 1 there is a refrigerating apparatus which includes a refrigerant flow conduit having a portion 4, or condenser coil, wherein the refrigerant is condensed, the condenser or portion 4 being disposed in the tank 1 for cooling by the water in the tank. The type of refrigerating apparatus

shown includes a refrigerant evaporator coil 5, a refrigerant compressor 6 and a liquid refrigerant receiver 7, but it will be understood that my invention is applicable to other types of refrigerating apparatus. The outlet end of the evaporator coil 5 is connected to the inlet or

suction side of the compressor 6 by a return conduit 8, and the receiver 7 is connected to the inlet of the evaporator coil 5 by a supply conduit 9. The outlet of the compressor 6 is connected to the inlet of the condenser coil 4 by a conduit 10, and the condenser coil is connected to the liquid refrigerant receiver 7 by a conduit 11. Any suitable control device, as at 11a, may be employed to control the admission of the refrigerant medium to the evaporator coil 5.

Surrounding and enclosing the condenser coil 4 in spaced relation thereto there is a conduit 12 having end portions 13 extending externally of the tank 1 and surrounding portions of the conduits 10 and 11. The ends of the conduit 12 are closed and sealed by solder or other suitable means, as at 14. The end portions 13 of the conduit 12 are connected in communication by a vertically extending conduit 15 which cooperates with conduit 12 to provide a closed continuous 20 circulatory conduit system. In the circulatory system water or other suitable liquid is contained. The water in the conduit 12 preferably completely fills the annular space between the inner wall surface of the conduit 12 and the outer 25 periphery of the conduit or condenser coil 4, and serves to conduct the heat of the condenser coil to the conduit 12 for transfer to the water in the tank 1. The liquid or water in the circulatory system circulates therethrough by gravity, due 30 to the difference in temperature between the portion of the conduit 12 within tank 1 and the temperature of the end portions 13 of conduit 12 and connecting conduit 15 located externally of the tank. As the water in the circulatory system 35 circulates it also absorbs heat from the conduits 10 and 11 and conveys the heat into tank 1 for abstraction by the water in the tank.

Preferably a container 16 is connected into the upper conduit portion 13 of the water circulatory system to provide an expansion chamber for the water and also to provide an opening for filling the circulatory system. In the top wall of the container 16 there is preferably provided an air vent, as at 17, for the escape of air to 45 atmosphere. A water level gauge 18 may also be associated with the container 16 for indicating the quantity of water in the water circulatory system.

By providing the conduit 12 enclosing the condenser coil 4, it will be seen that contamination of the domestic water supply by the refrigerant in the event of a leak in the coil 4 will be prevented. If a leak should occur in the condenser coil 4, the refrigerant medium would flow into the water in 55

the surrounding conduit 12 and escape through the air vent 17 instead of escaping into the tank 1. It has been found that under normal conditions the water of a domestic cold water supply system can be employed to cool a refrigerant condenser without appreciably increasing the temperature of the water, or without increasing the temperature of the water to a degree which would be objectionable. However, to safeguard against undue increase in the temperature of the water in tank 1, a temperature responsive valve, designated in general by the numeral 20, may be employed for opening a port to drain water from the tank upon increase in the temperature of the water to a predetermined temperature. The valve 20 may be mounted on the top wall of the tank 1 and may comprise, in general, a valve body 21 having a port controlled by a valve member 22 actuated by a temperature responsive element 23 enclosed by a casing 23 which may extend into the water in tank 1. A drain pipe 24 may be connected to the valve body 21 for the passage of water to the sewer when the valve member 22 is opened by the temperature responsive element 23. When the valve member 22 is open, the relatively warm water adjacent the top of tank 1 will flow out of the tank through conduit 24 to the sewer, while cold water will enter the tank through the inlet 2 until the temperature of the water in the tank decreases such that the temperature responsive element acts to close the valve member 22.

In the operation of the herein described system, gaseous refrigerant is withdrawn from the evaporator coil 5 by the compressor 6 and compressed, after which the compressed refrigerant is delivered by the compressor through conduit 10 to the condenser coil 4. The refrigerant in the coil 4 is condensed, giving up its heat to the surrounding water in conduit 12 which conducts the heat to the conduit 12 from which it is absorbed by the water in tank 1. The liquified refrigerant flows from coil 4, under the action of the compressor 6, through conduit 11 to the receiver 7 from whence it flows through conduit 9 to the evaporator coil 5 under control of the control device 11a.

In Fig. 3 there is shown another manner in which a refrigerant condenser may be cooled by the domestic water supply without danger of the refrigerant contaminating the water in the event of a leak developing in the condenser. In this instance the condenser, designated by the numeral 25, is located externally of the tank 1 and is surrounded and enclosed by a tank or container 26 which constitutes a part of a liquid circulatory system that has a conduit portion 27 located in the tank 1, the portion 27 preferably being coiled so as to have a large conduit surface area in heat transfer relation with the water in the tank. The container 26 is connected to the inlet end of the coiled conduit 27 by a conduit 28 and is connected to the outlet end of coil 27 by a conduit 29. The continuous circulatory system is preferably completely filled with a suitable heat absorbing and heat conducting liquid such as water, and in the conduit 28 between the container 26 and the coil 27 there is provided a pump 30 for circulating the water through the closed circulatory system. The compressor 6 is provided with a water jacket 6a surrounding the compressor head and connected in the conduit 29 of the circulatory system so that the heat generated by the compressor will be carried away by the water in the circulatory system

for transfer to the water in tank 1. The heat of condensation of the refrigerant in condenser 25 is given up to the water flowing through container 26 and conveyed by the water to the coiled conduit portion 27 in tank 1 where the heat is absorbed by the water in the tank. The relatively colder water leaving the coiled conduit portion 27 passes through conduit 29 to and through the compressor head, cooling the same and returning to the container 26. As in the system of Fig. 1, it will be seen that in the event of a leak in the condenser coil 25 the refrigerant will escape into the circulatory system and not into the tank 1.

The system shown in Fig. 4 is similar to that of Fig. 3 but differs therefrom in that the coiled conduit portion 27 is not located in the tank 1 but instead is located in a tank 32 which is connected at top and bottom to the main tank 1 by conduits 33 and 34, respectively. By reason of the relatively warm coiled conduit portion 27 in tank 32 there will be gravity circulation of the water flowing from one tank to the other, which will aid in carrying away the heat of the coiled conduit portion. The relatively warm water at the bottom of tank 1 will flow through conduit 34 into tank 32 and rising will cool coil 27 and flow through the upper conduit 33 and back into the tank 1. It is thought that the operation of the systems of Figs. 3 and 4 will be apparent from the description of the operation of Fig. 1.

What I claim and desire to secure by Letters Patent of the United States is:

1. In a system of the character described, the combination of a domestic water supply tank, a closed continuous liquid circulatory system having a portion thereof positioned in the water in said tank and having a container externally of said tank, a refrigerating apparatus including a condenser positioned in the liquid in said container, the liquid circulating through said system transferring the heat of said condenser to the water in said tank, and pump means to circulate the liquid through said circulatory system.

2. In a system of the character described, the combination of a domestic water supply tank, a closed continuous liquid circulatory system having a portion thereof positioned in the water in said tank for heat transfer relation therewith and having a container externally of said tank, a refrigerating system including a compressor having a head connected in said circulatory system and a condenser positioned in the liquid in said container and operatively connected to said compressor, and pump means for circulating the liquid in said circulatory system to transfer the heat of the compressor and the heat of the condenser to the water in said tank.

3. In a system of the character described, a domestic water supply tank, a second tank, said tanks being connected together for gravity circulation of the water, a closed continuous liquid circulatory system having a portion thereof positioned in the water in said second-named tank and having a container externally of said second-named tank, a refrigerating apparatus including a condenser positioned in the liquid in said container, the liquid circulating through said system transferring the heat of said condenser to the water in said second-named tank, and pump means to circulate the liquid in said circulatory system.

LEWIS W. EGGLESTON.
